(57) **CLAIM**

The ornamental design for an assembly for cooking elongated food products, as shown and described.

DESCRIPTION

FIG. 1 is a front perspective view illustrating my design for an assembly for cooking elongated food products;

FIG. 2 is a left side elevation thereof;

FIG. 3 is a front elevation thereof;

FIG. 4 is a right side elevation thereof;

FIG. 5 is a rear elevation thereof;

FIG. 6 is a top plan view thereof; and,

FIG. 7 is a bottom plan view thereof.

The broken/dashed-lined disclosures in the figures, including the raised dimples along the sides of the assembly, are for illustrative purposes only and form no part of the claimed design.
